(57) **CLAIM**

The ornamental design for a puzzle table, as shown and described.

DESCRIPTION

FIG. 1 is a perspective view of a puzzle table showing my new design, shown in a first configuration of use; FIG. 2 is another perspective view thereof; FIG. 3 is another perspective view thereof; FIG. 4 is a front elevational view thereof; FIG. 5 is a rear elevational view thereof; FIG. 6 is a left side elevational view thereof; FIG. 7 is a right side elevational view thereof; FIG. 8 is a top plan view thereof; FIG. 9 is a bottom plan view thereof; FIG. 10 is a partial enlarged view of the encircled portion 10 shown in FIG. 2; FIG. 11 is a partial enlarged view of the encircled portion 11 shown in FIG. 2; FIG. 12 is a partial enlarged view of the encircled portion 12 shown in FIG. 2; FIG. 13 is a partial enlarged view of the encircled portion 13 shown in FIG. 2; FIG. 14 is a partial enlarged view of the encircled portion 14 shown in FIG. 3; FIG. 15 is a perspective view of the puzzle table shown in a second configuration of use; and, FIG. 16 is a perspective view of the puzzle table shown in a folded state.

The dash-dash broken lines in the drawings depict portions of the puzzle table that form no part of the claimed design. The dot-dash broken lines represent boundaries of the enlarged portions and form no part of the claimed design.

1 Claim, 16 Drawing Sheets
